MOTION PICTURE PROJECTOR CASE

Raymond Herman, Brooklyn, N.Y., assignor to Richmond Research Corporation, Richmond Hill, N.Y., a corporation of New York

Filed Dec. 17, 1963, Ser. No. 77,835

Term of patent 14 years

(Cl. D61—1)

FIG. 1 is a side elevational view of a motion picture projector case showing my new design, the opposite side being substantially a mirror image thereof;

FIG. 2 is a top plan view thereof;

FIG. 3 is a bottom plan view thereof;

FIG. 4 is a right-end elevational view thereof; and

FIG. 5 is a left-end elevational view thereof.

I claim:

The ornamental design for a motion picture projector case, as shown and described.
